ROBERT H. INGERSOLL, OF NEW YORK, N. Y.; CHARLES S. SMITH, OF LANSING, MICHIGAN, AND FREDERIC C. LEUBUSCHER, OF ESSEX FELLS, NEW JERSEY, EXECUTORS OF SAID ROBERT H. INGERSOLL, DECEASED, ASSIGNEES TO ROBT. H. INGERSOLL, INC., OF NEW YORK, N. Y., A CORPORATION OF NEW YORK

RAZOR-BLADE STROPPER

Application filed September 16, 1926. Serial No. 135,915.

This invention concerns razor blade holders for employment during the stropping of the blade.

Among the objects of this invention are to provide certain combinations of elements which enable the quick and cheap manufacture of this type of devices; which facilitate the operations of placing and removing the razor blade; and provide a simple and flat assembly for such structures.

With these and other objects in view, as will appear hereinafter, two forms of execution are shown on the accompanying drawings.

Figure 1 is a plan view of a first form of execution, with the parts in the stropping position.

Fig. 2 is a similar view with the parts in opened position, with a portion cut away for clearness of disclosure.

Fig. 3 is a longitudinal section on line 3—3 of Fig. 1.

Fig. 4 is a plan view of the second form of execution, with the parts in the stropping position.

Fig. 5 is a similar view with the parts in the opened position.

Fig. 6 is a longitudinal section on line 6—6 of Fig. 4.

In the first modification, shown in Figs. 1 to 3 inclusive, the grip portion of the handle is a hollow sleeve 10 formed by folding sheet metal to form a flattened tube. The blade holder comprises the sheet metal member 11

having the studs 12 thereon to engage the razor blade B, which in the specific illustration is of the double-edged type with central apertures to receive the studs. The holder member 11 is continued at the handle end

40 by the strap 14 which is integrally joined to it by the arched bridge 15. The strap 14, at the right-hand end in the figures, is folded over upon itself so that the rebent extension 16 lies upon and parallel to the strap 14; and terminates short of the arched bridge 15.

The tubular handle 10 fits over the strap 14 and its rebent extension 16, and carries a pin 17 which moves in a slot 18 in the rebent extension and is thereby retained against withdrawal from around these members.

At the left-hand end, the holder 11 is likewise rebent and has a hinge eye 19 at the extreme end of the metal.

The second blade holder member 20 is formed at the left-hand end and with a 55 curled finger 21 to engage in the eye 19 for pivotal movement. This member 20 has an arched bridge 22 opposite the bridge 15, and extends therebeyond as a spur 23 which in closed or stropping position lies upon and 60 parallel to the strap 14, and terminates short of the rebent extension 16 of the latter, so that when the hollow handle 10 is slid leftwards, it passes onto this spur and in this way locks the two blade holder sections together and in clamping relation with the blade B.

Fig. 7 is a longitudinal section on line 7—7 of Fig. 4. The guard is composed of a single sheet of metal which is cut out to form a hollow rectangle with the two guard bars 24, the 70 outboard brace 25 and the inboard brace 26, the latter being bent at its middle section into a plane at right angles to the plane of the remainder of the guard. A pin 27 with an enlarged head 28 is located within the bight 75 between the eye 19 and the holder 11; and extends through a median hole in the brace 25, to serve as a pivot for the guard and preferably is located with its axis coinciding with the axis of the blade B when in stropping 80 position.

The inboard brace 26 likewise has a hole to receive a rivet 29 which is secured in the metal of the arched bridge 15 and has an enlarged head 30 to prevent the removal of the 85 brace 26 therefrom. The hole is larger than the shank of the rivet so that a rocking movement about the longitudinal axis of the blade is afforded.

In order to remove a blade from the holder, the hollow sleeve 10 is drawn towards the right in the figures until it uncovers the spur 23. The blade holder member 20 is then swung upward about its pivot at 21, and the blade B is fully disclosed and ready for removal, (Fig. 2). A new blade may now be placed in position, and by a reverse operation, the holder 20 is brought down upon it; and held in position by sliding the sleeve 10 to the left.

In the second form of execution, according to Figs. 4 to 6 inclusive, the two handle elements 40 and 41 are pivoted together at the left-hand or holder end by a pin 42, and may be held in clamped relation to each other by the clips 43 at the right-hand or handle end. These handle elements have the bridge portions 44 as before, and the blade holder sections 45 integral with each to support the razor blade B. The lower handle element 41 has the studs 46 on its holder to support the blade as before, and is formed at the outboard end of the holder with the upwardly bent flange 47 to carry the pivot pin 48 for the guard.

The guard in this instance is formed of wire crushed at the middle of its length and perforated to receive the pivot pin 48. The outboard end is straight to form a support 49 for the guard bars 50 which are spaced at a suitable distance from the pivot, and at the inboard end extend inward toward the handles. Opposite the bridges 44, the guard bars are bent towards the handles and enter the same and are then bent at 50° towards the free end of the handle. A metal strap or clip 51 is fastened about the free ends of the wire to hold it in its proper position. A base 52 is fastened rigidly to the lower handle member 41, and carries a spur 53 which is received in the clip 51 between the two ends of the wire and constitutes the second pivot for the guard.

This device is employed by disengaging the clips and swinging the upper handle about its pivot pin 42 into the position shown in Fig. 5, in which the blade is exposed and may be removed and a new one placed in position. By a reverse operation the members are brought together and clamped upon the new blade.

In each instance it will be seen that a stiff guard is provided, illustrated as being integral, and which presents its guard bars at a regulated spaced and parallel relationship with the edges of the blade in the holder. The contact of the bridges with the portions of the guard which enter between the handle members at those points assures a limitation of the rocking movement of the guard in its displacement from one face of the blade to the other, and the stiff assemblage of the guard itself maintains the parallelism of the bars with the edges of the blade.

The invention is not limited to the particular illustrations employed, but may be modified within the scope of the appended claims.

What is claimed as new is:

1. In a razor blade stropping device, a handle having a blade holder connected therewith, said holder including elements to support the blade rigidly with regard to the handle for stropping, one of said elements having its end bent out of plane, a rocking

guard comprising a rigid frame and guard rods spaced from and parallel to the edges of the blade when in stropping position, a pivot pin supported in said bent end, and supporting said guard, and a journal for said guard fastened to said bent element adjacent the opposite end thereof.

2. In a razor blade stropping device, a handle, a blade holder, said holder including elements to support the blade rigidly with regard to the handle for stropping, a bridge connection between said handle and holder to define a guide slot, a rocking support pivoted at its inner end with respect to the holder and having a portion passing through said slot and limited thereby in its rocking movement, a guard connected to the outer end of said support and including a portion extending parallel to the edge of a razor blade located in said holder, and means at the free end of the holder to support the guard in its rocking movement.

3. In a razor blade holder for stropping, a tubular handle, two blade holding elements pivoted together at one end, one of said elements being permanently located in said handle and the other of said elements being receivable in said handle by a relative sliding movement whereby to clamp the elements together upon a razor blade, a guard pivoted to said permanently restricted element for rocking movement with regard to said blade, and means formed integrally with said elements to limit said guard in its rocking movement.

4. In a razor blade holder for stropping, a tubular handle, two blade holding elements pivoted together at one end, said handle being slidable on the other end of one of said elements and adapted to slide onto and up from the other of said elements whereby to clamp and to free said elements from a razor blade, a guard of hollow rectangular form pivotally mounted at the pivotal end of said elements and entering by the said elements at the handle end thereof, means on one of said elements to support the entering portion of said guard, said elements forming a stop to limit the rocking movement of said guard.

In testimony whereof, I affix my signature.

ROBERT H. INGERSOLL.
